UNITED STATES PATENT OFFICE.

JOSEPH C. NORWOOD, OF SAN FRANCISCO, CALIFORNIA.

MULTIGRAPH TYPE.

Application filed May 31, 1927. Serial No. 195,355.

This invention relates to improvements in type cast in slug form similar to the ordinary line of type for use in that form of printing machine wherein the bed plate is 5 transversely slotted to receive individual type and has lips overhanging such slots to enter grooves formed in opposite sides of such type when the type are inserted into the slots of the bed plate through one end 10 of the latter.

The principal object of this invention is to produce an integral line of type or slug which may be slid into a slot in the bed plate of such a machine, thereby obviating the usual labor of setting up individual type.

A further object is to produce a slug or line of type which may be formed in a machine for producing lines of type and later be broken from the main body of the slug.

20 A still further object is to produce a device of this character wherein the form of the line of type is such as to automatically center and hold itself in the bed plate.

A still further object is to provide slugs 25 formed from a minimum amount of metal and which will nest during shipment thereby taking up a minimum amount of space.

Other objects and advantages will be apparent during the course of the following description.

In the accompanying drawings forming a part of this specification, and in which like numerals are employed to designate like parts throughout the same,

35 Figure I is a perspective view of a type slug and body portion, as the same appears when cast.

Figure II is an end view, on an enlarged scale, of one of the type slugs shown in Figure I,

40 Figure III is a view similar to Figure II, showing the body portion broken away from the type slug,

Figure IV is a view similar to Figure II 45 of a slug and body portion of the form produced when casting type of small size,

Figure V illustrates the manner of using the form of slugs of Figure IV in the bed plate of a printing machine of the character referred to above and showing the bed plate in cross section,

50 Figure VI illustrates the manner of using slugs of the form shown in Figure II of the bed plate of such a machine, which bed plate is shown in cross-section, and

55 Figure VII is an end elevation of a num-

ber of the slugs packed in lapped relation thereby taking up but half the amount of shipping room which would be otherwise necessary.

60

In the employment of printing of the character referred to it is necessary to set up the type from which the printing is to be done, which setting up operation is a tedious one due to the small size of the individual type 65 which are hard to handle and therefore easily dropped.

I have therefore perfected a type slug wherein the individual type are cast in a line upon a slug body, after which the whole 70 is ejected from the casting machine and the head or line of type is broken away from the body of the slug and then employed for printing purposes.

I am aware of the fact that various attempts have been made to accomplish this object, but due to the fact that square shoulders were formed upon the slugs these lines of type could not be readily ejected from the molds in which they were produced without 75 employing a complicated mechanism for opening the molds, which mechanism is impractical for use with the standard forms of machines for casting lines of type.

By forming a type slug having cam surfaces, I have perfected a type slug which may be readily ejected from the type forming machine.

In the accompanying drawings wherein for the purpose of illustration is shown a 90 preferred embodiment of my invention, the numeral 5 designates the type face which is cast upon the head 6 of the slug. Depending from the head 6 is a web portion 7, which web portion is flared so as to form 95 cam surfaces 8 and 9 adjacent the rear end of the line of type slug.

The base 9' of the slug is connected to the remainder of the slug by a restricted portion 11, in such a manner that cam surfaces 100 12 and 13 are formed upon the forward end of the base.

In the construction shown in Figure IV, it will be noted that the head 6 is narrower than the portion on which the cam surfaces 105 8 and 9 are formed. This permits the construction of small point type and it will also be noted that in this modified form the cam surfaces 8 and 9 are connected directly to the head 6, the purpose of which will be 110 later seen.

In use that portion of the slug which car-

ries the type face is broken away from the slug body as indicated at α , in Figure III, after which the type bearing slug portion may be slid into the bed plate of the printing machine, which bed plate is indicated at 14 of Figures V and VI.

The cam surfaces 8 and 9 will bear against the under-surface of a slot in the bed plate and thus automatically position the type 10 bearing slug centrally with respect to the slot, and at the same time will prevent the slug from moving away from the face of the bed plate. Heretofore, it has been impossible to employ small point type or slugs 15 in the slotted bed plate of a printing machine but by forming the slug as indicated in Figure IV, a bed plate construction as indicated in Figure V may be made which will permit type slugs of small point to be used.

20 It will be further noted that the base of the slug is cut away as shown in Figures I, II, III and IV so as to form a flat shoulder 15 and a cam surface 16. The cam surface 16 has the same pitch as the cam surfaces 8 and 25 12, that is to say, it is parallel with the latter surfaces, the result being that, during the ejecting operation, the cam surfaces will ride over the inclined surfaces of the two members of the mold in which the slug is 30 formed, thus evenly lifting the cap member of such mold from the back to the front of the latter.

The cutting away of the base of the slug as just indicated also permits the shipping 35 of the slugs in a nested condition, as shown in Figure VII which takes up much less

space in packing, and further when type slugs are packed in this manner, greater rigidity is given to the package and therefore there is less liability of mutilation of the 40 slugs.

It will thus be seen that I have provided a type slug having peculiar characteristics which will perform all of the objects above set forth.

45 It is to be understood that the forms of my invention herewith shown and described are to be taken as preferred examples of the same, and that various changes relative to the shape, material, size and arrangement 50 of parts may be resorted to without departing from the spirit of the invention or the scope of the subjoined claim.

Having thus described my invention, I 55 claim:—

A type slug for use in a printing machine having a bed plate provided with transverse type-receiving slots, comprising a type bearing member, a web portion having its inner extremity flared outwardly and rearwardly to form cam surfaces, a connecting body portion adapted to be removed therefrom, said body portion having cam surfaces formed parallel to said first mentioned cam surfaces, and being cut away substantially half of its width to form a shoulder substantially parallel with the head of the type bearing member and a cam surface parallel with one of said first mentioned cam surfaces.

60 In testimony whereof I affix my signature.

70 JOS. C. NORWOOD.
